Inventor
Edward M. Stephenson
by Seymour Pearce
Atty

UNITED STATES PATENT OFFICE.

EDWARD M. STEPHENSON, OF HARTFORD, CONNECTICUT.

PORTABLE LETTER FILE.

Application filed May 22, 1922. Serial No. 562,714.

To all whom it may concern:

Be it known that I, EDWARD M. STEPHENSON, a citizen of the United States, residing at Hartford, in the county of Hartford and 5 State of Connecticut, have invented a new and useful Improvement in Portable Letter Files; and I do hereby declare the following, when taken in connection with the accompanying drawings and the characters of 10 reference marked thereon, to be a full, clear, and exact description of the same, and which said drawings constitute part of this application, and represent, in—

Fig. 1 a perspective view of a portable letter-file constructed in accordance with my 15 invention.

Fig. 2 a face view, showing the device in a partially open position.

Fig. 3 a broken plan view, illustrating the 20 separation of the index sheets.

Fig. 4 a transverse sectional view.

Fig. 5 a view illustrating the manner of 25 folding letter sheets in the file.

Fig. 6 a broken, sectional view, illustrating 30 the manner of separating the index sheets into sections.

This invention relates to improvement in portable letter-files, that is, a holder in which letters may be filed so as to be readily 35 accessible, and adapted particularly for the use of traveling salesmen who are required to carry a large number of papers which must be always accessible, and the invention consists in the construction as hereinafter 40 described and particularly recited in the claim.

In carrying out my invention, I employ a back 10, side flaps 11 and 12, bottom flap 13 and top flap 14. Preferably, the side flap 11 45 will be provided with a strap 15 carrying members 16 of snap-fasteners which engage with members of snap-fasteners 17 fixed to the flap 12, and the top flap 14 will also be provided with snap-fastener members 18 to engage with snap-fastener members 19 on the bottom flap 13. Secured to the inner 50 face of the back 10 is a backing 20, to which is connected a series of leaves 22 provided with hinges 21, so as to provide an extension file, the several leaves being lettered in the usual way. As the length of the leaves is about one-half that of a sheet of business

letter paper, it is necessary to arrange the leaves in two sections for the purpose of indexing, and the bottom leaf of the upper 55 section is connected to the upper leaf of the lower section by an extension-strip 25, and to the bottom part of the upper section I apply a tab 23, by which the upper section of the leaves may be drawn to one side, as indicated in Fig. 3 of the drawings, so as to expose the indexed edges of all of the leaves. These leaves are preferably provided with integral tongues 24, or metal tongues may be applied to the leaves. The letters are 60 filed between the various leaves, one edge entering beneath the tongues 24, and their upper ends projecting above the file leaves, as shown in Fig. 2 of the drawings, and the upper portions of the letters may be readily 65 folded over the outer face of the index leaves, as indicated in Fig. 5 of the drawings, and when so folded the side flaps are turned inward and engaged, the bottom flap turned up and the top flap turned down and 70 engaged therewith, so as to produce an attractive package in which a large number of letters may be carried in a comparatively 75 small space.

To examine any particular letter, it is 80 only necessary to open the flaps and turn the top parts of the letters outward. Then, if the letter is in the lower section of the file, the top section will be moved to one side, so as to expose the indexes of the lower section, permitting the letter sheets filed under 85 any letter to be readily accessible.

I claim:

A portable letter-file, comprising a back, side flaps, bottom flap and top flap, a series 90 of independent index leaves connected with the said back and opening sidewise, said index leaves arranged in sections connected by an extension strip, a tab applied to the lower part of the top section, whereby that 95 section may be drawn to one side, and means for connecting the said flaps.

In testimony whereof, I have signed this specification in the presence of two subscribing witnesses.

E. M. STEPHENSON.

Witnesses:

FREDERIC C. EARLE,
MALCOLM P. NICHOLS.
